KEYING CIRCUIT

Harold Joseph Hughes Wassell, Widford Grove,
Chelmsford, England, assignor to Radio Corporation of America, a corporation of Delaware

Application November 16, 1938, Serial No. 240,641
In Great Britain December 1, 1937

3 Claims. (Cl. 178—66)

This invention relates to keying circuit arrangements for radio and like transmitters and has for its object to provide improved keying circuits for radio and the like transmitters of the kind wherein there is a plurality of high frequency stages in cascade one or more of said stages being keyed in and out of the "cut-off" condition thereby to remove the high frequency drive from a succeeding stage or stages and one or more of the succeeding stages being simultaneously keyed in and out of a condition in which considerable "dead loss" current is taken, thereby improving the regulation since, when the high frequency drive is cut off by an early stage or stages, the total load upon the energizing power source is still maintained at a value more or less approximating to, or a considerable percentage of, that obtaining prior to such cut off, by the action of the "dead loss" tube or tubes. By the term "dead loss" current, applicant means power loss in the anode circuit of a valve under direct-current conditions. In most known transmitters of the kind referred to the necessary changes in the operating conditions of the stages are brought about by suitably changing the grid biasses upon the stages in question, the usual practice being to derive the biasses from a resistance which is in series with a keying tube and suitable anode voltage supply source therefor, the grid potential of the keying tube being controlled by a key or the like which accordingly controls the current flow through the said resistance and therefore the biasses applied to the high frequency stages. Such a known circuit arrangement offers the practical defect that the said resistance must be of low value as compared to the grid impedances of the high frequency stage since high frequency stage grid currents flowing in the "mark condition" must flow through the said resistance. The necessity for a low value of resistance in turn involves a necessity for a high current flow therethrough to develop the required bias potentials therein and this in its turn involves the use of a large and expensive keying tube and associated anode potential source. The principal object of this invention is to avoid the above defect.

According to this invention a keying circuit for a radio or like transmitter of the kind referred to and wherein the two required keying biasses for the high frequency tubes—namely the cut-off bias for one stage or stages and the "dead loss" bias for a later stage or stages—are obtained from a potentiometer resistance in circuit with a keying tube is characterized in that there are also provided two auxiliary tube stages connected to

receive control biasses from said resistance one of said auxiliary tube stages being shunted between the point of application of one of said keying biasses and the end of said resistance and the other of said auxiliary tubes being shunted between the point of application of the other of said keying biasses and said resistance and the biasses applied to said auxiliary tube stages, in keying, being such as to render them conductive when grid currents are occasioned in the appropriate high frequency stages. When grid current flows in the high frequency stages my invention provides two paths through which it may flow, i. e., the additional tube impedances and the said resistance. As a consequence the resistance, keying tube and plate supply source, therefore, may be smaller.

The invention is illustrated in the accompanying drawing which shows diagrammatically one embodiment of the invention as applied to a radio transmitter having five high frequency stages—represented by the rectangles 1, 2, 3, 4, 5—in cascade, of which the second (2), third (3), and fourth (4) are keyed together into and out of the non-conductive condition and the fifth (5) is simultaneously keyed into and out of the "dead loss" condition. It will, of course, be appreciated that the invention is not limited to its application to transmitters with this particular number and arrangement of stages.

Referring more in detail to the figure the grid circuits of the second, third and fourth stages 2, 3, 4 are connected to the cathode 6 of a first auxiliary tube 7 whose anode 8 is connected to earth and to the cathode 9 of a keying tube 10. The grid circuit of the fifth stage 5 is connected to the cathode 11 of a second auxiliary tube 12 whose anode 13 is also connected to the cathode 9 of the keying tube 10. A bias source 14 in series with a key 15 (or relay contacts) is connected in the grid-cathode circuit of the keying tube 10 whose anode-cathode circuit consists of an anode potential source 16 in series with a potentiometer resistance 17. Any other keying means well known per se may, of course, replace the bias source and key or relay contacts in the grid-cathode circuit of the keying tube 10. The end 18 (or a point near the end) of the resistance 17 adjacent the negative terminal of the anode potential source 16, is connected to the control grid 19 of the first auxiliary tube 7 the cathode 6 of which is connected to a point 20 further down on the resistance 17. The control grid 21 of the second auxiliary tube 12 is connected to a point 22 near the earthed end of the resistance 17 and the cath-

ode 11 of said auxiliary tube 12 is connected to a point 23 still nearer said earthed end. If desired, and preferably, all the points 18, 20, 22, 23 on the potentiometer resistance 17 may be made adjustable as indicated.

5 In the "mark" condition (when the keying tube 10 is not conductive and accordingly the grids of the auxiliary tubes 1, 12 are at approximately the same potentials as the associated cathodes) the 10 said tubes present low internal resistances and thus allow the major portion of the grid current from the high frequency stages to flow through them in preference to flowing through the relatively high potentiometer resistance 17. The positions of the taps 18, 20, 22, 23 are so chosen that 15 at "space" (when the keying tube 10 becomes conductive), the auxiliary tubes are biased to cut off and at the same time the cathodes of said tubes assume the potentials necessary for the 20 second, third and fourth stages 2, 3, 4, to swing to cut-off and the fifth stage 5, to "dead loss."

As will now be appreciated the potentiometer 25 resistance 17 can be made of quite high value, while the keying tube 10 can be quite small and 25 the anode potential source 16 therefor also small, e. g. capable of supplying only a few milliamperes.

What is claimed is:

1. In a keying system, a plurality of relay 30 stages each comprising a tube having a control grid and cathode, a source of potential and a resistance connected in a series circuit, means connecting points on said resistance between the cathode and control grid of at least one of said tubes, an additional tube having its impedance 35 connected between points on said resistance, to shunt a portion of said resistance connected between said control grid and cathode, an impedance variable at signal frequency in shunt to said series circuit, said variable impedance serving to 40 vary the potential drop in said resistance and the bias between said control grid and cathode to

render the said first tube conductive or non-conductive, and a connection between the control grid of said additional tube and said resistance at a point on said resistance which biases said additional tube to a point at which its impedance 5 is low when said first tube is conductive.

2. In a keying system, a plurality of relay stages each comprising a device having a control grid and cathode, a source of potential and a resistance connected in a series circuit, means connecting points on said resistance between the cathode and control grid of two of said devices, a first tube having its impedance connected between points on said resistance to shunt a portion of said resistance connected between the control 15 grid and cathode of one of said devices, a second tube having its impedance connected between points on said resistance to shunt a portion of said resistance connected between the control grid and cathode of the other of said devices, an 20 impedance variable at signal frequency in shunt to said series circuit, said variable impedance serving to vary the potential drop in said resistance and thereby vary the bias between the control grids and cathodes of said devices to vary the 25 conductivity thereof between a high and low value and connections between the control grids of said first and second tubes and said resistance at points on said resistance which bias said additional tubes by potentials such that the impedances thereof are low when said devices are highly conductive.

3. A keying system as recited in claim 2 wherein 30 said variable impedance comprises a keying tube having an anode, a cathode, and a control 35 grid, means connecting the anode and cathode of said keying tube with said series circuit, and means connecting the control grid of said keying tube to a source of variable potential.
